[57] **CLAIM**

The ornamental design for a wall plate, as shown and
described.

DESCRIPTION

FIG. 1 is a perspective view of a wall plate showing our new
design;

FIG. 2 is a front elevational view thereof;

FIG. 3 is a back elevational view thereof;

FIG. 4 is a right elevational side view thereof;

FIG. 5 is a left elevational side view thereof;

FIG. 6 is a top plan view thereof;

FIG. 7 is a bottom plan view thereof;

FIG. 8 is a perspective view of a second embodiment of a
wall plate showing our new design;

FIG. 9 is a front elevational view of the second embodiment;

FIG. 10 is a back elevational view of the second embodiment;

FIG. 11 is a right elevational side view of the second
embodiment;

FIG. 12 is a left elevational side view of the second
embodiment;

FIG. 13 is a top plan view of the second embodiment; and,

FIG. 14 is a bottom plan view of the second embodiment.
The rear internal portions shown in broken lines for illus-
trative purposes only are not visible from the front, and are
not part of our design.
